RUDOLF DAERING, OF NORTON, ALBERTA, CANADA

LEVEL CROSSING GATE

Application filed October 11, 1930. Serial No. 488,086.

My invention relates to improvements in automatically operated level crossing gates, farm and other gates, and the objects of my invention are to eliminate the dangers arising from careless and unobservant pedestrians and vehicle drivers where highways cross railroads, and to provide convenient means of opening and closing any gate automatically.

10 I attain these objects by the mechanism illustrated in the accompanying drawings, in which—

Fig. 1 shows a front view of the gate seen from the railroad track.

15 Fig. 2 shows a plan view of gate with railroad track added.

Fig. 3 shows a side elevation of the gate and mechanism.

Fig. 4 shows a side section of contact trip-
20 ping device.

Fig. 5 shows an end view in part section of Fig. 4.

Fig. 6 shows a plan view of Fig. 4.

Fig. 7 shows a detail of angle braces on
25 the gate.

Fig. 8 shows a detail of the stop-disc with ratchet and pawl.

Similar numerals refer to similar parts throughout the several views.

30 Referring to the drawings:

1 and 1A represent two vertical gate posts supported on which is a sliding gate 2, the said gate being suspended from a pair or more of grooved pulleys 3 mounted on a horizontal shaft 4 which shaft is journaled on the said gate posts 1 and 1A. The gate 2 is composed of a framework projecting across the front faces of the posts when viewed as illustrated in Fig. 1. The said gate frame 2 has vertical angle braces 5 attached to its inside or rear face which project in such a manner as to form suspension points to carry the gate by means of cable connections 6 between the said angle braces 5 and the said pulleys 3, the cables 6 being wound around the pulleys and anchored thereto. Flanged rollers 7 are mounted on axle rods 8, the said rods being journaled in horizontally slotted holes 9 in the upper and lower ends of the vertical angle braces 5, each rod 8 carrying one of the

rollers 7 at each end. Springs 10 are inserted intermediate the axle rods 8 and the frames 2 of the gate for the purpose of maintaining pressure between the front members 2 and the gate posts 1 and 1A, and between the two pairs of grooved rollers 7 and the rear faces of gate posts 1 and 1A. Vertical rails 11 are attached to the front and rear faces of the posts 1 and 1A, in the front to reduce the friction between the gate frames 2 and the posts, and in the rear to act as guides for the grooved rollers 7.

The motive power for raising the gate is derived from a spiral spring 12 which is mounted on a shaft 13, the said shaft being journaled in bearings 14 and having a stop disc 15 loosely mounted on the same shaft 13. The spring 12 has its outer end attached to the support or foundation 16, and its inner end attached to the shaft 13. A toothed ratchet disc 17 is keyed to the shaft 13 immediately adjacent to the free running stop disc 15, and the rotation of the said ratchet 17 is controlled by a spring operated pawl 18 engaging the teeth of the said ratchet 17, the said spring of the said pawl being rigidly attached to the stop disc 15.

On the extreme end of the shaft 13 nearest the gate a toothed pinion wheel 19 is keyed which pinion is meshed with a vertically disposed spring-winding rack 20 attached to and projecting downwards from the gate framework 2, the said rack being housed in a vertical casing 20A which is sunk through the foundation and into the ground. The disc 15 is cam shaped on its lower semicircle as shown, the radius of the disc circle being reduced until the cam formed terminates in a stop 21, approximately on the horizontal diameter of the disc when the disc is in its normal position, and when observed as in Figs. 1 and 3. A stop-dog 22 is pivoted on the foundation 16 and engages against the said stop 21 holding the pawl 18 in engagement with a tooth of the ratchet 17 against the action of the spring 12. A stop lever 23, forming a right-angled projection from the pivoted stop-dog 22 acts as a check for a pin 24 attached at right angles to the lower face of the disc 15. The object of this pin is to

prevent the disc from turning when the spring 12 is being wound up, and this pin is also the means of ensuring the return of the dog 22 into the cam-stop 21 at the proper time when it comes in contact with the upper slightly tapered surface of the stop-lever 23 while the disc 15 is being turned by the spring 12 to raise the gate as described later. A bevel spur wheel 25 is mounted loosely on the shaft 13 towards that end near the gate, the said spur wheel being rigidly attached to the hub of the disc 15. This spur wheel 25 is mitered with a similar bevel spur wheel 26 which is keyed to a vertically disposed shaft 27 journaled in bracket bearings on the adjacent gate post 1A. Another bevel spur wheel 28, at the top of the shaft 27, is mitered with a similar bevel spur wheel 29 mounted freely on the aforementioned horizontal shaft 4. A clutch 30 is mounted on the said shaft 4, the driving portion of which clutch is rigidly attached to the said spur wheel 29, and the driven portion of which is slidably mounted on the shaft 4 over a feather-key, the jaw faces of the two portions of the said clutch being kept together during the lifting process by a helical spring 31. The jaw faces of the said clutch are separated by means of a forked clutch lever 32 conveniently fulcrumed on the adjacent gate post 1A, the movement of the said lever being controlled by the pull of a tension cable 33 attached to the end of the lever 32 opposite to the clutch. The said cable 33 passes down below the foundation 16 and is bifurcated in opposite directions passing over pulleys 34 to distant operation contacts 35 and 36 shown in plan view and explained in detail later. A spring cable tightener 37 is fitted to the top of the gate post 1A co-operating with the clutch spring 31. A lever 38 forms a straight line projection of the stop lever 23 and also forms part of the dog 22, being similarly fulcrumed on the foundation 16. The operation of this lever is controlled by a depression link 39, which link is depressed automatically by the passing vehicle by means of the operation contact 40. In order to operate two gates simultaneously the link 39 is bridged across below the operation contact 40. The lever 38 is returned to normal by the compression spring 40A attached to the foundation 16.

In explanation of the successive operations of this device it may be stated that a train or vehicle travelling in the direction shown by the arrow on the closing contact device 35 depresses a contact spring 41 as shown in Fig. 4, and lowers a plunger 42 rigidly attached thereto. The said plunger has tension adjustment holes 43 at its lower hooked end for attachment to the tension cable 33, said cable passing over two grooved guide pulleys 44 and thence over one of the pulleys 34 to operate the clutch lever 32 for disconnection of the clutch 30, thereby allowing the gate to

descend by its own weight. The rack 20 will rotate the pinion wheel 19 and the shaft 13 to wind the spring 12. When the spring 12 is fully wound the pawl 18 locks the ratchet teeth and holds the free running disc 15 against the stop-dog 22 until such time as the downward pressure is applied to the link 39 when the vehicle passes over the opening contact device 40. At this moment the dog 22 becomes disengaged from the disc stop 21 and the spring 12 unwinds and rotates the disc 15 in the direction of the arrow in Fig. 3, spur wheels 25, 26, 28 and 29 rotate, and the clutch being closed the gate is drawn up by the rotation of pulleys 3 and cables 6. The contacts 35 and 40 are placed a sufficient distance apart to insure that they are not operated simultaneously, as also are contacts 36 and 40. Should a train or other vehicle be travelling in the opposite direction as shown by the arrow at the closing contact 36 exactly the same procedure takes place and only one opening contact 40 common to both directions, will be required, and only two contact rollers will be necessary on the train or vehicle to complete the raising and lowering of the gate. Springs 45 attached to the gate posts 1 and 1A or to the rails 11 act as a stop for the height limit of the gate when open.

The semicircular spring 41 in the contact tripping devices 35 and 36 is anchored at one end 41A and free at the other end 41B in order that the tongued end 41B may slide freely when the vehicle is passing as shown for the contact 35, and vice versa when passing as shown for contact 36, both ends of the said spring 41 are, however, free to slide in the release contact device 40. These contact devices consist of circular angle-iron frames 48 with one leg of the angle-iron turned inwards to protect the spring 41 against the weather, circular cheek plates 49 on either side of the device, and holding down plates 50 and bolts 51. Contact 40 differs from contacts 35 and 36 illustrated in Figs. 4, 5 and 6, in that the spring 41 is not anchored at either end, and that it terminates in a sliding tongue at each end, also that the pulleys 44 are not required since the post 42 presses directly on the bridge or lever 39.

It is to be understood that whereas one gate only is shown in the illustration, two gates are in operation at the same time, one on each side of the track, also that under certain circumstances one gate only may be conveniently employed as on highways.

A housing 46 is shown by broken lines to enclose all the moving parts at the head of the gate, and another housing 47 is shown to enclose all the motive parts operating the gate. Under certain conditions it may be necessary to substitute reduction gearing in place of the single spur wheel 19 meshing directly with the rack 20.

What I claim as my invention, and desire to secure by Letters Patent, is—

1. In an automatically controlled slidable gate of the type described, a spiral spring driving motor, a ratchet and pawl check for winding the said spring in combination with a stop disc and independent stop-dog to hold the spring, a stop pin and independent stop lever to hold the said stop disc while winding, a toothed spur wheel meshing with a rack attached to the slidable gate for winding the said spring when the said gate is closing by reason of its own weight, a release lever to throw out the said stop-dog from holding the said stop disc, a lever or a bridge to operate the said release lever by a downward motion, a contact device comprising a spring depression member with a plunger post attached to automatically depress the said lever or bridge, and two pairs of meshed bevel gears for the transmission of the necessary power to raise the said gate, all as set forth.

2. In an automatically controlled slidable suspended gate of the type described, gate posts, a suspension shaft and pulleys, a spring controlled clutch to permit the raising of the said gate, a system of tension transmission cables controlling the said clutch, contact tripping devices to automatically pull the said cables for lowering the said gate, a spring motor automatically wound up by the falling action of the said gate under its own weight, a rack on the gate meshing with a spur wheel on the motor shaft to effect the winding up of the said spring, a ratchet operating with the said spring, a stop disc running loose on a shaft supporting the motor mechanism, a pawl attached to the said disc and meshing with the said ratchet, stop-dog holding and releasing levers controlling the rotation of the said stop disc, a pin stop to check the turning of the said stop disc when the said spring is being wound up, an automatic contact spring depression device controlling the said stop-dog, holding and releasing levers, and bevel spur wheels for angular transmission of the motive power from the motor to the gate raising shaft, all substantially as set forth in the specification and drawings.

RUDOLF DAERING.
